MACHINE FOR LOADING ENVELOPES

William H. Alden, Jr., Bryn Athyn, Pa.

Application February 14, 1940, Serial No. 318,837

14 Claims. (Cl. 93—6)

This invention relates to a machine for inserting material into an envelope and then sealing the envelope, if desired, preparatory to mailing, and is especially concerned with improvements in this type of device which will greatly broaden its usefulness particularly in circularizing or invoicing large numbers of addressees.

The principal objects of the invention are as follows:

1. To provide a machine of the character described which is capable of folding a letter or circular and then inserting it, either with or without a return envelope or postal card or other supplementary matter, into a mailing envelope and finally sealing the loaded envelope, if so desired, preparatory to mailing it;

2. To provide a machine capable of performing the functions enumerated above which is entirely automatic in its operation and in which all of the more essential moving parts receive 20 their motion from a single reciprocating member, which latter can be driven in any desired manner, manually or by a motor;

3. To provide a machine of the character described having means for opening the flap of the 23 envelope into which the material is to be inserted and then positively gripping the flap and pulling the envelope free of the supply stack so as to place it in the proper position to receive the material with which it is to be filled or loaded;

4. To provide a device which will positively open the back of the envelope after the flap has been opened so as to insure adequate entrance space for the material which is to be inserted into the envelope;

5. To provide a suitable compartment for receiving the loaded envelope with which is associated certain gripping means adapted to hold the envelope while the material inserting member is being withdrawn therefrom, and also to hold the inserted matter so as to avoid all possibility of any or all of the material being dragged out of the envelope as the inserting member is withdrawn; and

6. To greatly simplify mail handling machines as well as to reduce their cost of manufacture while at the same time increasing their capabilities and enlarging their field of usefulness, to lighten and make them more compact and, in general, to improve their efficiency and dependability and speed up their operation.

How the foregoing, together with such other objects as may appear hereinafter or are incident to my invention, are obtained is illustrated

in preferred form in the accompanying drawings, wherein—

Figure 1 is a side elevation of my improved machine;

Figure 2 is a vertical longitudinal section taken approximately as indicated by the line 2—2 of Figure 3;

Figure 3 is a plan view with certain portions broken away as indicated in order to more clearly illustrate some of the details;

Figure 4 is a fragmentary sectional view on an enlarged scale illustrating certain details of the invention associated with the envelope sealing means;

Figure 5 is a fragmentary sectional view, also on an enlarged scale, illustrating certain details of the invention relating to the envelope opening means and showing the material just about to be inserted into the envelope; and

Figure 6 is a fragmentary side elevation of a portion of the machine in order to show certain features of the mechanism for supplying return envelopes or other supplementary matter which are to be inserted into the envelope to be mailed.

By referring to the drawings it will be seen that the machine includes a suitable housing or supporting framework having side members 7 and 8 and end members 9 and 10. This structural supporting work, however, forms no part of the invention and it will be obvious that it could take any form which may be convenient or desirable, although I prefer to fabricate it from suitable sheet metal stock properly braced and reinforced where necessary. The various mechanisms for performing the several operations of my improved machine are all carried by this framework, and each in turn, both as to structure and operation, will now be described.

I will refer first to the mechanism for imparting an initial fold in the letter or circular to be inserted in an envelope. This mechanism comprises a blade 11 pivotally mounted at the sides upon the supporting arms 12, which latter swing around the pivot pin 13. The blade proper forms one face of a suitable triangular framework 14 to the upper portion of which is pivoted a pair of fingers 15 which are yieldingly urged toward the blade by means of the coil spring 16. The pivot for the fingers 15 takes the form of a transversely extending rod 17 to which the fingers are rigidly attached so that they will move therewith when the rod is rotated. One end of the rod is bent to form a crank member 18 by means of which the portion 11 may be rotated slightly in order to bring the fingers 15 away

from the face of the blade 41. In the position shown in Figure 2 the fingers are adapted to hold a card 19, or other supplemental matter, to be inserted into an envelope, which card is released when the parts assume the position shown in Figure 1, where the crank portion 18 of the pivot rod 17 has contacted the stop member 20 which holds the member 17-18, together with the fingers 15, against further movement while the blade 41 continues its movement a short additional distance, as will be described just below. As is clear from the drawings, this action moves the fingers 15 away from the blade 41 and permits the card 19 to fall by gravity.

While in the position shown in Figure 2, a sheet of paper, i. e., a letter or a circular 21, is placed upon the upper plate 22 of the machine with approximately one-third of its length extending to the right of a slot 23 through the plate 22, and the other two-thirds to the left of said slot. As the blade 41, in its downward swing, comes into contact with the paper, it forces it in the beginning of a fold down and between a pair of creasing rollers 24 and 25, as clearly shown in Figure 1. The roller 25 is yieldingly held in position by means of a pair of springs 26, one at each end, which springs react between the bearings for the roller and a suitable supporting abutment 27 through which latter there slides a guiding rod 28.

The rollers are preferably rubber faced, and the roller 24 is continuously driven in any desired manner as by means of a small motor 29 and a belt 30. As soon as the paper 21 contacts the rollers it is, of course, seized by them and passed downwardly along the dot and dash line 31 shown in Figure 1. In the meantime, the card 19 or other supplemental matter has been discharged into the fold or crease and is carried on through the rollers together with the paper, and when the operation is completed the paper carrying this supplemental matter assumes a vertical position within a V-shaped trough or retaining member 33, as shown by the dot and dash lines 32-34. V-shaped guiding members 34, with a slot between them at the bottom, are provided for properly guiding and holding the paper in its vertical position ready for the second fold which will be imparted in a manner to be described hereinafter.

The motion required by the blade 41 is imparted by virtue of the crank 35 rigidly attached near one end of the hinge pin 13. A rod 36 connects the free end of the crank 35 with the upper end of an actuating lever 37, which latter is pivoted upon a mounting 38 at a point intermediate its ends. A coil spring 39 normally urges this mechanism to the right so that the blade 41 assumes the position shown in Figure 2, from which position it is moved to perform the functions already described, by virtue of the fact that the lower end 40 of the operating lever 37 projects downwardly into the path of movement of a horizontally arranged, reciprocating blade 41, the purpose and function of which latter will be more fully described hereinafter. For the present it is simply noted that when this blade 41 moves to the right, it engages the end 40 of the lever 37 and moves it to the right, and finally causes the end 40 to ride on the upper surface 70 of the blade 41, as clearly shown in Figure 1, in which position the blade 41 has been moved to cause the initial crease or fold in the paper 21 and the supplemental matter 19 has been inserted therein.

The blade 41 is of substantially rectangular form as shown in dotted lines in Figure 3 where its left-hand edge is indicated by the reference character 41a and its right-hand edge by the reference character 41b. As will be seen, the blade is disposed in a horizontal plane and its length extends transversely of the machine. At its right-hand side it is provided with lateral extensions 41c and 41d. The end 41d is rigidly secured to a bearing block 42 which is mounted for longitudinal sliding movement along the guide rod 43. The end 41c projects over a guide rod 44 upon which it slides during reciprocation of the blade. The block 42 has an extended bearing upon the rod 43 so as to prevent all canting or cocking of the blade during operation of the machine. It will be understood, of course, that other methods of mounting the blade 41 for its reciprocating movement may be employed.

Motion can be imparted to the blade by means of the knob or handle 45 having a stem 46 which can be screwed into the block 42. Power can be applied either manually or by means of a suitable motor. A motor drive is not illustrated herein because the principles and main features of my improved machine are to be considered as being independent of any particular type of drive. In the present disclosure the power is manually applied by grasping the knob or handle 45 and moving it longitudinally of the machine.

Incidentally, in the further description of my invention, I will refer to the movement of the blade from right to left as its advancing movement and its movement from left to right as its retreating or return movement. In Figure 1, the blade 41 is shown in its extreme right-hand position just ready to begin the forward or advancing stroke, while in Figures 2 and 3 the blade is in its extreme left-hand position just ready to begin its return stroke.

Before proceeding with a further description of the purpose and functions of the blade 41, certain other features of the machine should now be described in order to lay a basis for a more logical presentation of the operation of the machine as a whole.

The envelopes to be loaded are stacked in a horizontal position in a suitable compartment 47 with their flaps 48 facing downward and arranged at the right-hand side of the stack. At one side the edge of the stack rests upon a short horizontal shoulder 49, and at the other side on another ledge or shoulder 50, which latter inclines downwardly from the horizontal at a slight angle, as shown most clearly in Figure 4. Experience has shown that an angle of approximately 45° yields best results for most envelopes, although a slight adjustment or variation in this angle may possibly be necessary for some types or weights of envelopes. No definite rule as to the angle to be employed can be given, but a little experiment will quickly demonstrate what is the most satisfactory angle for any particular set of conditions.

The angle or slope of the shoulder or ledge 50 and the fact that it projects inwardly toward the envelope only a comparatively short distance has an important bearing on the ease with which each envelope can be removed from the supply or feeding stack 47.

In the functioning of my improved machine, an envelope is removed from the feeding stack, opened and placed in position to receive the material with which the envelope is to be loaded,

and the nature and operation of this portion of the device will now be described.

As the blade starts its return stroke the rear edge of its extension 41c first comes into contact with the downwardly projecting end of an actuating lever 51 which forms, as it were, one foot of a link 52. The other foot 53 comes into play on the forward or advancing stroke of the blade, as will be described later, and the two feet 51 and 53 unite to form the body portion 54 which effects the connection to the link 52. The link 52 is pivotally connected at 55 to a guide arm 56 which swings around a pivot 57. An inwardly projecting lug 58 on the end of the arm 56 is adapted to come into contact with the upper edge of the link 52 when the arm 56 and the link 52 assume a horizontal position, such as shown in Figure 1. This acts as a stop and prevents too great a degree of movement in the downward direction.

As will be clear from Figures 1 and 2, movement of the lever 51 to the right under the influence of the extension 41c of the blade 41, as just described, serves to swing to the right a pair of parallel links 59 and 60, the other end of link 52 being pivotally connected at 61 to approximately the middle of the link 59. The upper end of the link 59 pivots upon the pin 62 and the upper end of the link 60 upon the pin 63, there being a slot 64 in the link 60 by means of which a slight adjustment of the length of the arm 60 can be obtained in order to secure proper adjustment of what I have termed the flap opening blade 65, which is pivotally carried upon pins 66 and 67 at the lower ends of the arms 59 and 60. The angle of the flap opening blade 65 can be varied by increasing or decreasing the effective swinging length of the arm or link 60.

The arms 59 and 60 are duplicated—one set for each end of the blade 65—and, as they move to the right under the influence of the action of the blade 41 on the foot 51, as just described, the right hand edge of the blade 65 slips under the flap 48 of the lowermost envelope, which flap, of course, will be hanging downwardly slightly. As the motion to the right continues, the flap will be pushed around until it gradually assumes the position shown in Figures 1 and 5. Toward the end of its stroke the blade 65 will press the end of the flap 48 against the end of what I shall term a pressure bar 68 swung between the lower ends of a pair of links 69, the upper ends of which are also mounted upon the pin 62. Normally, the arms 69 and the pressure bar 68 which they carry are held in the position shown in Figure 2 by means of the L-shaped spring wires 70 reacting between a suitable portion of the supporting framework and the bars 69. The springs 70 are mounted upon pins 71 around which they fulcrum. A stop 72 prevents the bar 68 and its supporting arms 69 from swinging too far to the left under the influence of the springs 70. The bar 68 may be mounted in suitable slots 73 in the lower ends of the arms or links 69, so that its position may be adjusted slightly if necessary.

When the blade 65 presses the end of the flap against the bar 68, as just described, the flap is positively yet releasably gripped between the two members and as motion to the right continues the envelope is positively withdrawn from the shoulders 49 and 50 and pulled away from the supply stack 47 into the position shown in Figures 1 and 5. Motion of the envelope away from the ledge or shoulder 50 is greatly facilitated by the

slight inclination of this shoulder already described.

When the envelope has reached the position just described I have found it desirable, in order to ensure dependable operation, to positively open the back of the envelope, and this portion of the invention will now be described. The blade, of course, is still retreating, and when its rear edge 41b contacts the upper end of the lever 74 (which is shown in dotted lines in Figure 2 and in full lines in Figure 1), the lever 74 will be swung upon the pivot 75 to the position shown in Figure 1, with the upper end of the lever 74 finally contacting the under face of the blade 41. During this swinging movement of the arm 74 the back opening fingers 76 are swung to the position shown in Figure 1 by means of the mechanism now to be described. A pair of parallel links 77 and 78 is provided at each side of the machine and suitably carried on a portion 80 of the supporting structure. The links 77 are pivoted upon the rod 81 in such manner as to cause the links and the rod to rotate together, suitable adjustment being possible by virtue of the slots 82. The lever 77 at one side of the machine extends downwardly and carries at its lower end a balancing weight 83. Near one end the rod 81 is provided with a crank 84 which is connected by means of a rod 85 to another operating arm 86, the lower end of which pivots on the pin 87 and the upper end 88 of which is adapted to project into the path of movement of the blade 41 when the parts are in the position shown in Figure 1.

The lower ends of the links 78 are pivoted at 89 to the supporting structure 80. Between the upper ends of the links 77 and 78 is pivotally carried the envelope back opening device 90 which includes a blade-like part 91 and the spring fingers 76 already mentioned. As in the case of the flap opening device, this mechanism constitutes a parallel link mechanism which, by suitable adjustment, can be made to have the necessary motion for accomplishing the purpose described.

The link 74 is operatively connected to the link 77 by means of the tie rod 92 which pivots at 93 on the link 74 and at 94 on the link 77. The connecting rod 95 between the crank 84 and the arm 86 is also pivotally secured at its ends to the members which it connects. Near the upper portion of the link 77 which carries the weight 83 is connected a rod 95 which slides through a suitable cleat 96 and which carries at its end a spring 97 reacting between the cleat at the right and a nut or nuts 98 at the left, in such manner as to urge the back opening device to the left.

The operation of the back opening mechanism is as follows. As the blade retreats it contacts the upper end of the lever 74, and when it reaches its final right-hand position the parts of the back opening mechanism have assumed the position indicated in Figure 1. When the forward or left-hand stroke of the blade begins, the end of the lever 74 first comes out from under the blade 41 and as the blade continues its motion the spring 97 initially causes the parts to follow the blade, and as they do so the spring fingers 76 enter the back of the envelope and by virtue of their curvature serve to positively open the back of the envelope as clearly shown in Figure 5. The blade 41 carrying the matter to be loaded or inserted into the envelope still further advances and enters the open back, also as shown in Figure 5, passing over the ends of the spring clips 76 which yield in order to permit such insertion. As the blade continues its advance to the left it will

extend farther and farther into the envelope until such time as the envelope is positively moved and carried with the blade, at which time the flap 48 of the envelope is pulled free of the grip effected by the blade 66 and the bar 66. Finally, when the envelope is moved sufficiently far to the left to remove it from the fingers 76, the blade contacts the upper end 88 of the arm 86 and gives a sudden motion to the back opening mechanism which serves to throw the same quickly down into the position shown in Figure 2, where it is completely out of the way of the motion of the blade until such time as it again contacts the upper end of the arm 76 on its return stroke.

The extension 46 of the blade carries at its forward edge between the forked supports 90 a projecting actuating roller 100 which contacts the upper end 88 of the arm 86 as just described. During this stroke the roller 100 also actuates the foot 58 of the envelope flap opening and positioning mechanism by coming into contact with the rearwardly curved face of the foot 58. This latter contact operates to return the flap opening and envelope positioning mechanism to the position shown in Figure 2, where it is again ready to start the series of operations for which it was intended and as already described above.

Prior to the time that the blade 41 assumes its final left-hand position shown in Figure 2, it is necessary that certain other mechanism be moved, which mechanism relates to the receiving and sealing of a loaded envelope. This will now be described. A pusher box 101, preferably hollow, is mounted upon a supporting plate 102 which, in turn, is carried at the top of a pair of oppositely disposed vertically extending racks 103 which can be moved upwardly and downwardly by means of the pinions 104. The pinions are rigidly fastened to the operating shaft 105, rotation of which is effected by means of the driving sprocket 106 and operating chain 107, which also passes around the gear 108 at the other end of the machine. The chain is driven by connecting it to the pin 48 by means of a swinging link 109.

As will be seen by comparing Figures 1 and 2, when the actuating blade 41 is in its right-hand position, the pusher member 101 is in its uppermost position where it projects well into the envelope receiving stack 110, a pile of loaded envelopes being shown in this stack in Figures 1 and 2. In Figure 2, however, the pusher member 101 is in its lower or retracted position, and the blade 41, with the envelope which it has just loaded and moved, lies below the stack 110. As the blade is withdrawn to the right, the pusher 101 starts its upward stroke, and as it does so it lifts the loaded envelope upwardly and pushes it past the retaining shoulder 111 at the rear lower edge of the stack 110, the forward edge of the envelope having already been moved into proper position above the inclined side supports 112 and the central support 113. During this operation, the flap 48 of the envelope previously introduced into the receiving stack 110 is pressed upwardly against the back of the envelope and is sealed at the same time, by virtue of the fact that the inside of the flap has already been moistened on the previous down stroke of the member 101, as will now be described.

As stated, the member 101 is preferably hollow and is adapted to contain water or other sealing liquid. At the upper rear edge of the pusher 101 I arrange a projecting wick 116 which wipes against the inside of the flap 48 of the

loaded envelope which has just been deposited beneath the receiving stack 110, and the body of which envelope the member 101 has just forced into the bottom of the stack 110. As the member 101 descends, the wick 116 thoroughly moistens the adhesive on the flap 48, and after the member 101 reaches its lower position and the reciprocating blade 41 transfers another loaded envelope from the stack 41 to the stack 110, the previously moistened flap 48 is fully turned by the advancing loaded envelope to the sealing position shown in Figure 2. The weight of the envelopes holds the moistened flap sufficiently tightly against the back of the envelope to cause effective sealing thereof as the moisture dries.

The upper surface of the supports 112 is preferably made of rubber or similar material, which is capable of a slight gripping action on the material of the envelope. In place of a rubber surface, small pricks or pin-like points could be employed for the same purpose. Some provision of this kind is important for the reason that as the blade is withdrawn from the envelope, a tendency occasionally arises for the envelope to be moved back with the retreating blade. The provision of the rubber-covered supports 112 prevents this, because the weight of the stack of envelopes causes a gripping action against the supports which is just sufficient to prevent any tendency of the envelope to follow the blade as it is withdrawn from the envelope.

The central support 113 is primarily useful as a means for preventing the contents of the envelope from following the blade as it is withdrawn. By providing this small shelf-like space I find that the weight of the envelopes is sufficient to slightly grip the contents and thereby prevent withdrawal thereof as the blade returns to its right-hand position.

At this point I should like to call attention to the fact that the axes of the two envelope stacks 47 and 110 are parallel and that the operating faces of the two stacks are in substantially the same plane, the operating faces, of course, being the faces which lie adjacent the plane of the reciprocating blade 41. The envelope stacks are housed within suitable retaining structure which is made adjustable in any desired manner in order to take envelopes of different sizes. The details of this stack adjusting mechanism, however, will not be described as they form no part of the present invention and could, obviously, take any one of a number of different forms, any particular form being largely a matter of preferred design.

I will now return to a description of the manner in which the letter or circular receives its second fold and in which any other supplemental matter may be added to the material which the reciprocating blade 41 inserts into the envelope. As described, the paper with its first fold and with certain supplementary matter 19 already lying in this fold, as shown in dot and dash lines in Figure 1, stands in a substantially vertical position after the first fold has been imparted, the blade 41, of course, being at its extreme right-hand or retracted position. As the blade 41 advances to the left, it first picks up any other additional or supplemental matter, say, for example, a return envelope which it receives from the stack 110, which stack is suitably housed in a retaining structure or box 116.

This box 116 is suitably positioned and supported just above the path of movement of the

blade 41 and directly over the shelf 120, by means of the rearwardly extending positioning rods 117 and the laterally extended supporting angles 117a, which latter are preferably secured to the left-hand side of the box. They have a horizontally extending part shown to best advantage in Figure 3 and vertically extending parts which reach down to rest upon the side shelves 23a of the supporting framework through the intermediation of suitable adjusting screws 117b. The rods 117 have downwardly projecting hook portions 118 which project through the angle supports 119 secured to the rear wall 10 of the framework.

The shelf 120 is inclined slightly and upwardly from the right to the left as shown most clearly in Figures 2 and 6, and the supplemental matter is adapted to pass outwardly through a bottom opening in the compartment 116 and to rest upon the shelf 120. The slight incline of shelf 120 permits the flap of the supplemental matter to open slightly so as to catch the advancing blade as will further appear.

In this instance it will be assumed that the supplemental matter 115 consists of return envelopes, the flaps 121 of which are arranged downwardly with the apex of the flap pointing toward the rear wall 10, as shown to best advantage in Figure 6. As the blade 41 advances to the left it first encounters the flap 121 of an envelope in the stack 115, which envelope has come down sufficiently far to rest upon the inclined shelf 120 directly in the path of the oncoming blade. The blade picks up the envelope by passing between the flap and the body of the envelope and continues on its way, and when its advancing edge, with the envelope mounted thereon, encounters the upstanding letter or circular, it immediately starts a second fold or crease which is completed as the blade continues its passage through the rollers. Incidentally, the rollers 122 and 123 do not need to be driven as do the rollers 24 and 25 because the blade serves to carry the material all the way through. The lower roller 123 is yieldingly urged toward the upper roller 122 by means of the spring 124 in a manner entirely similar to that which was employed in connection with the roller 25.

Just before the blade reaches the rollers 122 and 123, it encounters a pair of swinging dogs 125 which are mounted upon pins 126, the pins being carried in lugs 127 which project forwardly from the lower portion of the container 116. The dogs 125 will then swing to the left under the influence of the continued movement of the blade until such time as the blade passes beneath their ends. In this way the dogs in no way interfere with the advancing motion of the blade. On the return stroke the rear edge of the blade contacts the dogs 125 which are then swung to the right and upwardly into the position shown to best advantage in Figure 6, this action serving to raise the envelope stack 115 out of the way of the returning blade. It will be noted that the container 116 and the shelf 120 are slotted slightly in order to permit the necessary motion of the dogs 125 to raise the envelopes in the box.

After passing through the rollers 122 and 123 on its stroke to the left, the blade with its letter or circular and other supplemental matter is moved forwardly and introduced into the already opened envelope as shown in Figure 5 and as previously described.

At this point I should like to call attention

to the fact that it is not necessary to limit the matter which is introduced by means of the container 116 to return envelopes as it is perfectly obvious that any other type of supplementary matter can be inserted, provided it is folded in such a way as to make possible a downwardly extending portion corresponding to the flap 121 of one of the envelopes in the stack 115. For convenience, such supplemental matter might be called "flapped" matter. I should also like to point out that by the simple expedient of lengthening the machine and the stroke of the blade it is entirely feasible to utilize a plurality of supplemental feeding stacks similar to the stack 116, the contents of each of which can be successively entrained or picked up by the blade during the course of its forward stroke. Of course, the bulk or thickness of any such supplemental matter introduced by successive compartments 116 would have to be not greater than can be conveniently handled by the blade and readily passed through the rollers 122 and 123, but it will be obvious that by proper design this feature of a succession of compartments 116 can be very easily incorporated in a machine of the character disclosed without in any way departing from the spirit of my invention.

Brief summary of operation

To begin with, of course, it is necessary that the compartment 47 be filled with envelopes which are to be loaded and that the box 116 contains a supply of whatever supplemental matter is intended to be included with the material to be mailed, such as the return envelopes 115. With the various mechanisms in the positions indicated in Figure 2, a letter or circular is placed in proper position upon the upper plate 22, the accurate positioning of the letter being aided by means of the upwardly and outwardly flared guiding pins 128. At the same time, a return postal card 19 or other supplemental matter of a similar nature is placed under the retaining fingers 15 on the initial folding blade 11. The horizontally reciprocating blade 41 is then moved from its left-hand position as shown in Figures 2 and 3, to the right. The first result of such motion is to bring the back of the blade against the downwardly extending leg 51 of the envelope flap opening mechanism, which thereupon causes this mechanism to open the flap 48 of the lowermost envelope in the stack 47 and to carry this flap around into the position where it is gripped between the edge of the member 65 and the pressure bar 68, as shown to best advantage in Figure 5. This action positively withdraws the lowermost envelope from the bottom face of the stack 47 and holds it in position to receive the material with which it is to be loaded when the blade 41 moves back to the left.

As the blade 41 continues its motion to the right, it passes through the rollers 122 and 123 and then comes into contact with the levers 37 and 74 which, respectively, operate the initial folding blade 11 and the back opening member 90, together with their associated parts. During the initial movement of the levers 37 and 74, the blade 41 also passes under the swinging dogs 125 which serve to raise the envelopes 115 and the compartment 116 as previously described, in order to permit the blade to reach its final retracted position as shown in Figure 1. During this final movement of the blade 41 the lever 37 moves from its dot-and-dash line position shown in Figure 1 to its full line position shown

In the same figure, which movement, as previously described, swings the blade 41 downwardly against the paper 21, thereby commencing the first fold or crease and introducing the paper into the grip of the rollers 24 and 25. Substantially coincidentally with this action the supplemental matter 19 is discharged into the crease or fold by virtue of the fact that the rod 18 abuts against the stop member 28, thereby moving the fingers 16 to the position shown in Figure 1, so that the card 19 can fall by gravity.

At the same time that the initial fold is thus being imparted, the lever 74 is moved from its dot-and-dash line position shown in Figure 2 to its full line position shown in Figure 1. This serves to bring the back opening plate 90 and its associated parts into the positions indicated in Figure 1, where they are just ready to begin the operation of opening the back of the envelope which is being held in position in the path of movement of the reciprocating blade 41.

It is now necessary to go back to the showing in Figure 3, in order to call attention to the fact that in this view the pusher device 101 which forces the loaded envelopes upwardly into the receiving stack 110 is in its lowermost position. As the blade 41 moves to the right in accordance with the summary of operation so far described, the chain 107 rotates the pinions 104 and raises the pusher 101 so as to force the loaded envelope which had been previously deposited at the bottom of the stack 110, upwardly into the stack as shown in Figure 1, which action turns the flap 48 of this loaded envelope into a substantially vertical position as shown in dotted lines in Figure 1.

Now with the parts in the position shown in Figure 1, the blade 41 begins its forward or left-hand stroke, and as it does so the following operation takes place. First, the upper end of the lever 74 comes out from under the back edge of the blade 41, whereupon the spring 87 moves the back opening member 98 sufficiently far to introduce the spring fingers 76 into the back of the envelope which is being held between the members 65 and 68. This action serves to open the back of the envelope as shown to best advantage in Figure 5. Just before this action is completed, the advancing blade 41 picks up the lowermost envelope 115 or other supplemental matter from the box 116 by virtue of the fact that the edge of the blade slips under the flap 121. The blade then carries this envelope past the dogs 125 (which swing out of the way to permit such movement) over against the initially folded letter or circular 21 which is standing in the vertical dot and dash position 31, 32, of Figure 1. Further movement of the blade 41 to the left passes the material between the rollers 122 and 123 on the way to the opened envelope which is waiting to receive it. This motion of the blade 41 releases the lever 37, thereby permitting the spring 99 to return the pivoted blade 41 to its upper or inoperative position as shown in Figure 2, where it is ready to begin another cycle of operations.

In the meantime, the pusher member 101 is moved downwardly and as it moves downwardly its wick 114 moistens the adhesive on the flap 48 of the loaded envelope which had previously been deposited in the bottom of the stack 110. This is most clearly shown in the enlarged view of Figure 4.

In its progress to the left the blade 41, carrying the material to be loaded into the opened

envelope, now reaches the envelope and advances all the way down into the bottom of the envelope, the spring fingers 76 yielding to permit passage of the blade and its load. When the bottom of the envelope is reached, the blade pulls the flap 48 free from the holding members 65 and 68 and then carries the loaded envelope over into position beneath the stack 110. After the envelope is loaded and carried away from the spring fingers 76, the blade 41 encounters the upper end 88 of the lever 86, thereby causing it to move to the left to the position indicated in Figure 2, which action moves the entire back opening mechanism downwardly out of the way with a rather quick motion, which, of course, is aided by gravity, although properly balanced by means of the counterweight 83. The pusher 101 has descended sufficiently far at this time to permit the action just described.

As the stack of loaded envelopes moves downwardly in following the downwardly moving pusher 101, the flap 48 of the lowermost loaded envelope rides against the edge of the retaining shoulder 111, which action serves to close the flap when the pusher has finally moved out of the way. The next loaded envelope will then completely close and seal the moistened flap.

One other function which is performed by the blade 41 in its forward or left-hand stroke remains to be mentioned. Just before the blade contacts the lever 86, it comes against the leg or foot 53 of the flap opening mechanism, thereby returning it to the position shown in Figure 2, where it is ready to begin another cycle of operations.

After the blade deposits the loaded envelope in the compartment 110 and starts its return movement to the right, there may be a slight tendency for the envelope and its contents to return with the blade, but this is overcome by the supports 112 and 113 previously described, which are preferably rubber faced, so that the weight of the envelopes in the stack 110 causes the bottom one to be slightly gripped and the contents pinched in the envelope. This positively holds the loaded envelope in its deposited position. In order to perform this function accurately during the loading of the first few envelopes, it will be necessary to introduce a slight weight on the top of the stack 110 which, of course, will rise as the envelopes accumulate in this stack. This, however, is not shown in the drawings but is simply placed upon the top of the envelopes in the stack 110.

In the device as disclosed herein, the blade 41 is reciprocated by grasping the knob 45 and manually moving it back and forth, but it will be readily appreciated that such reciprocating movement could be imparted mechanically as by means of a suitable electric motor. The letters or circulars 21 are laid successively upon the table 22 and the cards 19 introduced at substantially the same moment, with the parts in the positions shown in Figure 2. I should like to mention, however, that I have developed entirely automatic feeding mechanism for the letters 21 and cards 19, as well as a continuously operating driving mechanism for the blade 41, so that all manual operation can be eliminated. The details of these features, however, are not shown herein, but will be made the basis of additional applications.

As pointed out in the objects of the invention, I want to stress the fact that all of the important mechanisms which go to make up my im-

proved device receive their motion from a single reciprocating member, i. e., the member 41 which is a very valuable feature because it serves to reduce to as great an extent as possible the number and intricacy of the parts and mechanisms required to perform the desired functions.

Although the device which I have disclosed herein represents a preferred embodiment of my invention, I should like to call attention to the fact that many of the more important features of my invention can be incorporated in a machine which does not include the initial folding blade 11 or the folding rollers 122 and 123. In instances of this kind, all of the matter to be inserted or loaded into an envelope may be "flapped" matter and may be placed in a series of boxes 116 simply by extending the machine and lengthening the stroke of the blade 41, as previously indicated. On its advancing stroke the blade would then successively pick up a series of circulars or other material and introduce them simultaneously into an opened envelope in the manner already described.

I claim:

1. A machine for loading envelopes including a compartment for supplying empty envelopes, a compartment for receiving loaded envelopes, a compartment for supplying "flapped" matter with which the envelopes are to be loaded, the operating faces of said compartments being substantially in the same plane, a blade mounted for reciprocation across said operating faces, the blade being adapted to carry "flapped" matter from the compartment containing such matter to the compartment containing the empty envelopes and to insert such matter into an envelope and finally to deliver the loaded envelope to the compartment for receiving the loaded envelopes, and means for raising the "flapped" matter whereby to permit return of said blade to its initial position.

2. A machine for loading envelopes including a compartment for supplying empty envelopes, a compartment for receiving loaded envelopes, a compartment for supplying "flapped" matter with which the envelopes are to be loaded, the operating faces of said compartments being substantially in the same plane, paper folding means lying in the plane of the operating faces of the said compartments, a blade mounted for reciprocation across said operating faces, said blade being adapted to cooperate with the folding means to fold the paper and being further adapted to carry "flapped" matter from the compartment containing the same together with the folded paper to the compartment for supplying the empty envelopes and to insert such matter into an envelope, and finally to deliver the loaded envelope to the compartment for receiving loaded envelopes, and means for raising the "flapped" matter whereby to permit return of said blade to its initial position.

3. A machine for loading envelopes having a preliminary paper folding mechanism including a device for feeding supplemental matter into the fold, means for giving the paper a second fold, a compartment for supplying empty envelopes, and a reciprocating blade adapted to cooperate with said second folding means to fold the paper and then to transfer the folded paper with its contained supplemental matter into the first envelope of the compartment for supplying empty envelopes.

4. In a machine for loading envelopes, a compartment for supplying empty envelopes, said

compartment having an open end through which the envelopes are removed for loading, means for holding a stack of envelopes in the compartment with their flaps facing said open end so that the apex of the flap of the outermost envelope will project slightly beyond the plane of said open end, a flap opening member mounted to move behind the flap of the outermost envelope and to turn it outwardly to a position extending away from and in substantially the same plane as the body of the envelope, a movable member against which said flap is pressed by the opening member, the flap being gripped between said members, and means for moving said members with the flap gripped therebetween whereby to pull the envelope out of the stack.

5. In a machine for loading envelopes, a compartment for supplying empty envelopes, said compartment having a retaining shoulder at a side thereof against which the flaps are adapted to rest with their apices free thereof, a flap opening member mounted to move behind the flap and then to turn it outwardly to a position extending away from and in substantially the same plane as the body of the envelope, a movable member against which said flap is pressed by the opening member, the flap being gripped between said members, and means for moving said members with the flap gripped therebetween whereby to pull the envelope out of the stack.

6. The structure of claim 5, wherein the shoulder is sloped away from the opening in the compartment in order to facilitate the withdrawal of the envelope.

7. The structure of claim 4 together with a back opening element, means for inserting said back opening element into the removed envelope to open its back while the flap of said envelope is being gripped by said members, a reciprocating blade adapted to carry the material with which the envelope is to be loaded, and means for moving the blade into the opened envelope, the motion of the blade being adapted to release the loaded envelope from said gripping members and to carry it to a point of removal from the machine.

8. In a machine for loading envelopes, a compartment for supplying empty envelopes, said compartment having an open end for discharging the envelopes therefrom and the envelopes being arranged so that their flaps can project outwardly through said open end, means retaining the envelopes in said compartment until they are positively removed therefrom, a flap opening member mounted to move behind the flap and then to draw it outwardly to a position extending away from and in substantially the same plane as the body of the envelope, a movable member against which said flap is pressed by the opening member, the flap being gripped between said members, mechanism for moving said members with the flap gripped therebetween whereby to pull the envelope out of the stack, said mechanism including lever means projecting beyond the plane of the envelope which is being removed from the compartment, and a reciprocating blade mounted to move across the open end of said compartment, said blade, in one direction of its travel, being adapted to enter the opened envelope and to carry it away from said gripping members and then to engage said lever to retract the flap opening mechanism to its initial position.

9. The structure of claim 8, wherein the mechanism for moving the flap gripping members is provided with a second lever projecting beyond

the plane of the envelope which is being removed from the compartment, said second lever being adapted to be actuated by the reciprocating blade when traveling in the opposite direction whereby to effect the opening of the flap and withdrawal of an envelope as aforesaid.

10. The structure of claim 8, together with a member mounted upon parallel swinging links for opening the back of the envelope after it is withdrawn from the compartment, a lever for actuating the swinging links, said lever projecting into the path of movement of the reciprocating blade and being actuated by the blade during the envelope removing stroke to bring the back-opening member into position to open the back of the removed envelope, and a second lever for returning the back-opening member to its inoperative position, said last lever also projecting into the path of movement of the reciprocating blade and being actuated thereby during the stroke when the flap opening and envelope removing mechanism is being returned to its initial position.

11. In a machine for loading envelopes, the combination of a compartment for supplying empty envelopes; mechanism for opening the envelope flap and then withdrawing the envelope from said compartment; mechanism for opening the back of the withdrawn envelope; a compartment for holding matter to be inserted into said opened envelope; a compartment for receiving loaded envelopes; mechanism for pushing the loaded envelopes into said receiving compartment; and a reciprocating blade for taking matter from said holding compartment, inserting it into the withdrawn and opened envelope, and carrying it into position before the loaded envelope receiving compartment; all of said mechanisms being actuated by the reciprocating blade.

12. In a machine for loading envelopes, a pair of paper folding rollers, a blade mounted to move toward and away from said rollers to feed the paper therebetween, means on the blade for carrying supplemental matter and delivering it into the fold of the paper to be carried with the paper through the folding rollers, a compartment for supplying empty envelopes, a compartment for receiving loaded envelopes, a compartment for supplying "flapped" matter with which the envelopes are to be loaded, the operating faces of said compartments being substantially in the same plane, a paper folding means lying substantially in the plane of the operating faces of the compartments, and a blade mounted for reciprocation across the operating faces of said compartments, the folded paper from said folding rollers being arranged to lie across the path of movement of said reciprocating blade and said reciprocating blade being adapted to cooperate with the folding means in the plane thereof to fold the paper a second time, and said reciprocating blade being further adapted to carry "flapped" matter from the compartment containing the same into said second fold and to transfer the paper with said supplemental matter and said "flapped" matter to the compartment for supplying empty envelopes and then to insert such matter into an envelope, and finally to deliver the loaded envelope to the compartment for receiving loaded envelopes.

13. In a machine for loading envelopes, a compartment for supplying empty envelopes, said compartment having an open end through which the envelopes are removed for loading, means for holding a stack of envelopes in the compartment with their flaps facing said open end so that the

7 apex of the flap of the outermost envelope will project slightly beyond the plane of said open end, and means for gripping and pulling the flap to remove the envelope from the compartment.

14. The structure of claim 13 together with means for opening the back of the envelope while its flap is so gripped, and an envelope loading blade adapted to enter the opened envelope and pull it free of said flap gripping means.

15. A machine for loading envelopes including a compartment for supplying empty envelopes, a compartment for receiving loaded envelopes, a compartment for supplying "flapped" matter with which the envelopes are to be loaded, the operating faces of said compartments being substantially in the same plane, a blade mounted for reciprocation across said operating faces, means for removing an envelope from the supply compartment and holding it in the path of movement of said reciprocating blade, the blade in its movement in one direction being adapted to remove "flapped" matter from the compartment containing such matter and carry it to said open envelope and insert it therein and finally to deliver the loaded envelope to the compartment for receiving the loaded envelopes, and means for raising the supply of "flapped" matter in its compartment, said means being actuated by the reciprocating blade upon its motion in the opposite direction, whereby to permit return of said blade to its initial position.

16. A machine for loading envelopes including a compartment for supplying "flapped" matter with which the envelopes are to be loaded, a compartment for supplying empty envelopes, a compartment for receiving loaded envelopes, the operating faces of said compartments being substantially in the same plane, a blade mounted for reciprocation across said operating faces, means 40 below the plane of blade reciprocation for supporting the "flapped" matter, means above the plane of reciprocation of said blade for supporting the empty envelopes, means above the plane of reciprocation of said blade for supporting the loaded envelopes, means for withdrawing an empty envelope and holding it in open position in the path of movement of said blade, the blade being adapted in one direction of its travel to remove "flapped" matter from the bottom of the compartment for supplying such matter and carry it to and insert it into said open envelope and finally to carry the loaded envelope to a position below the compartment for receiving loaded envelopes, means for pushing the loaded envelope 45 into its compartment, and means for raising the "flapped" matter in its compartment, said means being actuated by the reciprocating blade upon its motion in the opposite direction, whereby to permit return of said blade to its initial position.

17. A machine for loading envelopes including a compartment for supplying empty envelopes, a compartment for supplying "flapped" matter with which the envelopes are to be loaded, the operating faces of said compartments being substantially in the same plane, a blade mounted for reciprocation across said operating faces, means below the plane of blade reciprocation for supporting the "flapped" matter, means above the plane of reciprocation of said blade for supporting the empty envelopes, means for withdrawing an empty envelope and holding it in open position in the path of movement of said blade, the blade being adapted in one direction of its travel to remove "flapped" matter from the bottom of the compartment for supplying such matter and

carry it to and insert it into said withdrawn envelope and finally to carry the loaded envelope to a point of removal from the machine, and means for raising the "flapped" matter in its compartment whereby to permit return of said blade to its initial position.

18. A machine for loading envelopes including a compartment for supplying "flapped" matter with which the envelopes are to be loaded, a compartment for supplying empty envelopes, a compartment for receiving loaded envelopes, the operating faces of said compartments being substantially in the same plane, a blade mounted for reciprocation across said operating faces, means beyond the plane of blade reciprocation for supporting the "flapped" matter in the path of movement of said blade, means for withdrawing an empty envelope and holding it in open position in the path of movement of said blade, the blade being adapted in one direction of its travel to remove the outermost piece of "flapped" matter from the compartment for supplying such matter and carry it to and insert it into said withdrawn envelope and finally to carry the loaded envelope to a position adjacent the compartment for receiving loaded envelopes, means for pushing the loaded envelope into the loaded

envelope compartment, and means for moving the "flapped" matter into its compartment whereby to permit return of said blade to its initial position.

19. A machine for loading envelopes including a compartment for supplying empty envelopes, a compartment for supplying "flapped" matter with which the envelopes are to be loaded, the operating faces of said compartments being substantially in the same plane, a blade mounted for reciprocation across said operating faces, means beyond the plane of blade reciprocation for supporting the "flapped" matter in the path of movement of said blade, means for withdrawing an empty envelope and holding it in open position in the path of movement of said blade, the blade being adapted in one direction of its travel to remove the outermost piece of "flapped" matter from the compartment for supplying such matter and carry it to and insert it into said withdrawn envelope, and finally to carry the loaded envelope to a point of removal from the machine, and means for moving the "flapped" matter into its compartment whereby to permit return of said blade to its initial position.

WM. H. ALDEN, JR.
